UNITED STATES PATENT OFFICE.

WILLIAM M. SAXTON, OF SPOKANE, WASHINGTON, AND CHARLES CLINTON HODGE,
OF WINNIPEG, MANITOBA, CANADA.

BOILER-WASHING SYSTEM.

1,089,272.

Specification of Letters Patent. Patented Mar. 3, 1914.

Application filed February 11, 1913. Serial No. 747,769.

To all whom it may concern:

Be it known that we, WILLIAM M. SAXTON, a citizen of the United States, and a resident of Spokane, in the county of Spokane and 5 State of Washington, and CHARLES C. HODGE, a citizen of the United States, and a resident of Winnipeg, in the Province of Manitoba and Dominion of Canada, have made certain new and useful Improvements 10 in Boiler-Washing Systems, of which the following is a specification.

Our invention relates to improvements in systems for washing out boilers of locomotives and it consists in the combinations, 15 constructions, and arrangements herein described and claimed.

An object of our invention is to provide means whereby the boilers of a plurality of locomotives, each under a different steam 20 pressure, may be blown off simultaneously without one interfering with the other, and any number may be washed out at the same time.

A further object of our invention is to 25 provide means for decreasing the back pressure in blow-off pipe, means for delivering water from the wash-out tank and a circulation maintained as hereinafter described.

A further object of our invention is to 30 provide an economical system in which all of the heated water is used, thereby economizing in heat, by passing through coils and refilling tank. The by-pass will be used in blow-off line if for any reason it would 35 be necessary to stop flow of water in blow-off from passing through refilling tank.

Other objects and advantages are apparent in the following specification and the novel feature of the system will be particularly pointed out in the appended claims.

Our invention is illustrated in the accompanying drawings forming part of this application in which,

Figure 1 is a sectional view through portions of the apparatus, certain parts, such as pipes, being shown in side elevation. Fig. 2 is a diagrammatic view of the pipes, showing connections to the boilers of locomotives.

In carrying out our invention, we provide 50 a tank 1, which is carried by a suitable foundation 2. This tank we will designate the wash-out tank. A similar tank 3 is supported on the piers or foundation 4 and 55 serves for the refilling tank. At 6 we have

shown a motor for driving the pumps 7 and 8, respectively.

Referring now to Fig. 2, we have shown at 9 and 10 boilers of locomotives. These boilers are arranged to be connected with 60 the different pipe lines, such as the blow-off line, the refilling line, and the wash-out line in the manner hereinafter explained.

The rest of the apparatus will be best understood by an explanation of the operation 65 of the system.

It will be understood that it is desirable to wash out the boiler of a locomotive when the boiler is heated. Formerly the practice was to let the water cool and to wash out the 70 boilers with cold water, which was injurious to the boiler, and it was found necessary to pump cold water into the boiler which contains hot water and to allow the water to pass out, thereby gradually cooling the 75 boiler preliminary to washing it out, but this required considerable time and therefore hot water is used instead. The trouble has been to blow out the boilers of two or more locomotives simultaneously when the steam in 80 these boilers was at different pressures.

With the systems in present use it is necessary to equalize these pressures before the washing out process can be completed, but with our system two, three, or four, or more 85 boilers may be blown off simultaneously even when the steam in the boilers is at different pressures, without interfering one with the other in the operation. Let us consider then that the two locomotives 9 and 10, 90 shown in Fig. 2, are to be washed out simultaneously. The locomotive 9 may have its boiler under a pressure of fifty pounds and the locomotive 10 may have one hundred and fifty pounds pressure. The boilers of 95 each of the locomotives are connected by means of the flexible pipes 11 with the blow-off pipe 12 leading to the blow-off line 13. Between the blow-off pipe 12 and line 13 are disposed T's 14. These T's are in the 100 nature of injector cones, that is, the ends 13a of the pipes are prolonged, as shown by dotted lines. The pipes 12 communicate with the outer part of the T at a point at one side of these ends. We will show later 105 how the cold water from the wash-out line tends to form a vacuum at the T's 14. We will assume that the steam and hot water passing through pipe 12 passes through the T's 14 and along the blow-off line in the di- 110

rection indicated by the arrow. The steam is condensed at T's 14 and passes through the coils in refilling tank to wash-out tank where sediment is deposited and may be drawn off through the pipe 16 into discharge pipe 17 which may communicate with the sewer or other outlet.

The refilling tank 3 is charged by means of cold water from any suitable source which passes through pipe 20 extending downwardly into tank 3 and is provided with float valve 21 which automatically shuts off the water when the tank is nearly full. Also exhaust or live steam from any source may pass into this tank through the pipe 22 and the heating is augmented by the coils of the blow-off line. As the steam is condensed and the water in the tank 3 is heated (if the wash-out process is not going on) this tank will overflow through pipe 25 into the wash-out tank. This provides an additional source of hot water for the wash-out tank. This wash-out tank is also connected by means of pipe 26 with the pipe 22 through which live steam enters and escapes through the perforated pipe at its end, thus heating the water in the wash-out tank. It may be that the temperature of the water in the wash-out tank will get too high. We have provided a vent pipe 27 which leads to the atmosphere by a back pressure valve 29. The lever of the back pressure valve is connected with a lever of valve 30 in pipe 31 which admits cold water from pipe 20 into tank 1. When two or more pounds pressure is developed in the tank 1 by the heating of the water, the back pressure valve 29 will act and will cause the opening of the valve 30, thereby letting cold water from the pipe 20 into the tank 1, thereby reducing the temperature and hence the pressure. The tank 1 is provided with a float valve 32 which will permit communication between the overflow pipe 33 and the drain pipe 17 leading to the sewer, when the tank 1 is filled up to the float 32. The tank 1 is also provided with a pipe 34 so that it may be filled with cold water from the pipe 20 preliminary to starting the device. The water is shut off by the float valve 35 when the tank is filled. It will also maintain water at float level as water is used for washing out purposes.

When it is desired to wash out the boiler, the pump 7 is started and the water is drawn from the bottom of the tank and is forced upwardly through the pipe 36 to the wash-out line 37. The latter is connected, as will be seen by reference to Fig. 2, with the pipes 38 to which suitable connections may be made with the boiler. Thus the hot water in the tank 1 may be forced through the boiler, thereby washing out sediment and scale. When now the pump 8 is started, the water from the refilling tank will pass by

means of the pipe 39 to the refilling line 15 and thence it may be conducted by means of pipe 40 into the boilers. The water in the refilling line is considerably above the temperature of the water in the blow-off line due to the passage of live steam into the refilling tank through which the blow-off line also passes. For this reason, we have placed a by-pass 41 in blow-off line so that water circulating through blow-off line will not be heated to a greater temperature than can be handled for washing out purposes. Cold water may be supplied to the wash-out tank while hot water is being used for washing out, same passing through circulating pipe 42 and as the water is forced into T's 14, condensation takes place at these points so that a partial vacuum is produced. This tends to aid the operation of the apparatus and to make it continuous by connecting the circulating pipe to blow-off line at 16. Two or more of the boilers at different pressures may be blown off simultaneously without interfering at all with the thoroughness and facility of the operation.

The value of a system of this kind may be easily seen. It is not necessary to bring the boilers of the locomotives to the same temperature in order to blow off the boilers. The boilers may be at once attached to their respective blow-off lines and the operation may begin. Owing to the fact that all of the heated water, such as that from the blow-off line, the overflow water from the refilling line, etc., is used in the operation, a great saving of heat and great economy in operation is the result.

Another feature to which we desire to call attention is the fact that owing to the arrangement shown in Fig. 1, either tank 1 or 3 may be used as the wash-out tank or the refilling tank. To this end we have provided the different valves and by-passes which can be easily traced on Fig. 1. This is for the convenience of repairs to one or the other of the tanks.

We claim:—

1. In a system for simultaneously washing out a plurality of boilers, the combination of a wash out tank, a blow-off line, connections between said blow-off line and each of said boilers at one end and between said blow-off line and said wash out tank at the other, a wash out line having connection with said wash out tank at one end and with said boilers at the other end, means for forcing water from said wash out tank through said wash out line into the boilers, means disposed in said blow-off line for condensing the steam from said boilers prior to its delivery to the wash out tank, a refilling tank surrounding a portion of the blow-off line and arranged to be heated by the passage of fluid through said blow-off line, and a refilling line connected with said refilling tank at

one end and having connections with each of said boilers at the other end of the line, said refilling line being connected with said blow-off line.

5. 2. In a system for simultaneously washing out a plurality of boilers, the combination of a wash out tank, a blow-off line, connections between said blow-off line and each of said boilers at one end and between 10 said blow-off line and said wash out tank at the other, a wash out line having connection with said wash out tank at one end and with said boilers at the other end, means for forcing water from said wash out tank 15 through said wash out line into the boilers, means disposed in said blow-off line for condensing the steam from said boilers prior to its delivery to the wash out tank, a refilling tank surrounding a portion of the 20 blow-off line and arranged to be heated by the passage of fluid through said blow-off line, a refilling line connected with said refilling tank at one end and having connections with each of said boilers at the other 25 end of the line, said refilling line being connected with said blow-off line, and means for heating said refilling line and said wash out tank.

3. In a system for simultaneously washing out a plurality of boilers, the combination of a wash out tank, a blow-off line, connections between said blow-off line and each of said boilers at one end and between said blow-off line and said wash out tank at the 30 other, a wash out line having connection with said wash out tank at one end and with said boilers at the other end, means for forcing water from said wash out tank through said wash out line into the boilers, means 35 disposed in said blow-off line for condensing the steam from said boilers prior to its delivery to the wash out tank, a refilling tank surrounding a portion of the blow-off line and arranged to be heated by the passage of 40 fluid through said blow-off line, a refilling line connected with said refilling tank at one end and having connections with each of said boilers at the other end of the line, said refilling line being connected with said 45 blow-off line, means for heating said refilling line and said wash out tank, said heating means comprising a live steam line, and a perforated pipe disposed in each of said 50 tanks and being connected with said live steam line.

4. In a system for simultaneously washing out a plurality of boilers, the combination of a wash out tank, a blow-off line, connections between said blow-off line and each of said boilers at one end and between 55

said blow-off line and said wash out tank at the other, a wash out line having connection with said wash out tank at one end and with said boilers at the other end, means for forcing water from said wash out tank 65 through said wash out line into the boilers, means disposed in said blow-off line for condensing the steam from said boilers prior to its delivery to the wash out tank, a refilling tank surrounding a portion of the 70 blow-off line and arranged to be heated by the passage of fluid through said blow-off line, a refilling line connected with said refilling tank at one end and having connections with each of said boilers at the other 75 end of the line, said refilling line being connected with said blow-off line, means for heating said refilling line and said wash out tank, said heating means comprising a live steam line, a perforated pipe disposed 80 in each of said tanks and being connected with said live steam line, a circulating line for connecting the wash out tank with the blow-off line and the refilling line, and means for forcing water from said wash 85 out tank through said circulating line into said blow-off line.

5. In a system for simultaneously washing out a plurality of boilers, the combination of a wash out tank, a blow-off line, 90 connections between said blow-off line and each of said boilers at one end and between said blow-off line and said wash out tank at the other, a wash out line having connection with said wash out tank at one end and 95 with said boilers at the other end, means for forcing water from said wash out tank through said wash out line into the boilers, means disposed in said blow-off line for condensing the steam from said boilers prior 100 to its delivery to the wash out tank, a refilling tank surrounding a portion of the blow-off line and arranged to be heated by the passage of fluid through said blow-off line, a refilling line connected with said refilling 105 tank at one end and having connections with each of said boilers at the other end of the line, said refilling line being connected with said blow-off line, a by-pass in said blow-off line 110 around the portion of the blow-off line within the receiving tank, and means for controlling said by-pass.
